UNITED STATES PATENT OFFICE.

VICTOR DENNIS COGLON, OF CALGARY, ALBERTA, CANADA.

ELECTRICAL INSECT DESTROYER.

Application filed February 12, 1927. Serial No. 167,844.

This invention relates to electrical insect destroyers as described in the present specification and illustrated in the accompanying drawings which form part of the same.

5 The invention consists essentially of the novel features pointed out broadly and specifically in the claims for novelty following a description containing an explanation in detail of an acceptable form of the invention.

10 The objects of the invention are to provide an efficient insect destroyer of simple construction, and relatively cheap of manufacture; and generally, to improve upon the 15 construction shown in a prior application filed August 5th, 1925, as Serial Number 48,331.

In the drawings, Figure 1 is a fragmentary elevation view of a typical door provided with a device built in accordance with 20 this invention;

25 Figure 2 is an enlarged fragmentary view showing the mode of insulating the horizontal and end vertical electric conductive members from the frame thereof;

Figure 3 is a sectional view taken on line 3-3 in Figure 1;

Figure 4 is a sectional view taken on line 4-4 in Figure 1;

30 Figure 5 is an enlarged fragmentary perspective view showing the mode of staggering the electric conductive members or elements;

Figure 6 is a fragmentary view of the 35 device, the frame being shown in dotted lines;

Figure 7 shows the mode of insulating the ends of the members 19;

40 Figures 8 and 9 show modifications in the construction of the electric conductive members.

Like numerals of reference indicate corresponding parts in the various figures.

Referring to the drawings, 10 designates a door formed with the vertical members 12, 45 the top cross member 11 and the intermediate cross-member 11^A; an open or panel space is provided within which is suitably secured or fastened the device, designated in its entirety by the numeral 12^A.

50 The device consists of a frame, preferably made of wood, to which is fastened two independent metal screens operatively connected to two terminals of an electric circuit, the screens, when assembled into the frame 55 to form the device complete, being staggered to leave equal distances between the conduc-

tive elements. The distance left between any two consecutive elements is made such that, when a fly or other insect attempts to pass therebetween, the distance or gap becomes short-circuited and the fly destroyed. 60

Each separate screen is made of a plurality of uniformly-spaced longitudinal metal elements or members 17 bent as at 20 and 21, and of the cross-members 19 and 18 welded, 65 soldered, or otherwise secured to the members 17. The members 19 are spaced at suitable intervals to impart as much rigidity to the members 17 as possible, consistent with economy; the members 18 are disposed flush 70 with the ends of the members 17. When two such screens are mounted upon or into the wooden frame to form the device complete, the members 17 are in a same plane; and one screen is applied upon the other in 75 such a way that the members 19 and 18 in each screen are parallel but spaced from one another, as clearly shown in Figures 3 and 5. The members 17, 18 and 19, which are made of some suitable metal, are preferably 80 rectangular in cross-section, inasmuch as this section facilitates the welding.

If found more economical each screen may be stamped from one single sheet of metal. 85

In order to insulate one screen from the other corresponding screen, as well as insulating the screens from the frame, suitable insulation must be provided.

A layer of some suitable plastic insulation material 23 is first applied so as to 90 insulate the cross members 18 from the frame, this layer being applied substantially as shown in Figures 2 and 6, over the entire length of the members; the ends of the members 19 are then wrapped around with 95 the same plastic insulation material, as shown in Figure 7, wherein the insulation is designated by the numeral 23^A.

A strip of insulation material 25, of fairly close texture, is then used to separate and insulate one screen from the other, as shown in Figure 2, and the strips which are horizontally-arranged are notched or depressed at 26 to provide a clearance or space to receive the covered ends of the members 19. 100

In order to facilitate the mounting of the screens in or upon the frame, the members 13 and 14 are formed to a substantially L-cross section, as shown in Figures 3 and 4, thus allowing the screens and the strip 25 105 to be applied separately and one at a time, after which these are securely retained in 110

place by means of a removable frame 27. This frame 27 is secured to the main frame in any suitable way; metal plates 28 may be secured at intervals to the frame by means 5 of screws 29.

31 and 32 designate two wires connected with the electric circuit, and passing through the frame member 13, one wire being operatively connected to any of the 10 members 19 of one screen, and the other wire being similarly connected to any member 19 of the other corresponding screen.

In assembling the screens, after the conductive members have been wrapped or insulated as already explained, one screen is laid into the depression or recess formed in the cross-section of the frame, the strip 25 next applied, and then the second screen. The second frame 27 is now applied and 20 pressed down, and the metal clips applied to securely hold said frame in place.

Figure 8 shows a modification in the construction of the screens, wherein the cross members 19^A are offset at intervals to form 25 ridges 20^A alternately receiving one member 17^A of one screen and clearing the adjacent member 17^B of the other screen, thus permitting of making the members 17^A and 17^B straight between the end offsets 21^A.

30 Figure 9 shows another modification in the construction of the screens, the two screen units being made exactly alike but

assembled into the frame so that the cross-^L members 19, instead of lying immediately above one another as in Figure 5, will be 25 slightly distanced from one another.

What I claim is:

1. In an electric insect destroyer, a substantially-rectangular frame having the members thereof recessed on one face to give 40 said members an L-cross-section, a pair of metallic screens mounted in said recess and separately wired to the source of electric power, a detachable frame fitting over the recessed face of said frame, and means for insulating said screens from one another and from said frames. 45

2. In an electric insect destroyer, a frame having a recess in one face thereof, a pair of symmetrically formed metal screens 50 mounted in said frame, each of said screens comprising a plurality of longitudinal conductive members and two end cross members and intermediate cross members raised from the plane of said longitudinal members, said cross members alone engaging said recess, means for insulating said screens from one another and from said frame, and means for separately wiring the screens to the source of electric power. 55 60

Signed at Toronto, Canada, this 5th day of February, 1927.

VICTOR DENNIS COGLON.
